SIGNALING SYSTEM AND MECHANISM
THEREFORErnest R. Freeberg, Moline, Ill., assignor to Eagle
Signal Corporation, a corporation of Massa-
chusetts

Application February 7, 1934, Serial No. 710,151

7 Claims. (Cl. 177—337)

This invention relates to signaling systems in which visual or other signaling aspects are alternatively or successively given, and is particularly suited for embodiment in signaling systems for controlling and directing vehicular highway traffic.

The rate of movement of vehicles upon main or so-called "arterial" highways has increased during the past decade to so great an extent that, if warning is merely given to drivers of vehicles that the right of way has been withdrawn from the highway upon which they are traveling and has been given to those who are likely to cross their path, vehicles which are approaching the crossing point or intersection at a time when a stop indication is given for them, are likely to be moving so rapidly that they will be unable to bring their vehicles to a stop before reaching the intersection; and, hence, will unavoidably enter upon or cross same at a time when the vehicles or pedestrians who have been given a "proceed" signal have moved into their path.

The situation thus developed is aggravated by the psychological tendency to attempt to get across the intersection without being delayed by the passage of traffic which is waiting to move across the path. Thus, it has been found that if, in a cycle of signal changes, an interval is provided for "clearing the intersection" during which "stop" signaling aspects for all traffic are displayed, drivers of approaching vehicles are prone to rely on such supposed period of grace when the stop signal appears, and to therefore speed up instead of slowing down their rate of movement. In fact, the result seems to be that inasmuch as they are permitted to pass the stop signal for at least a short interval after it appears, they are likely to misjudge, to a greater or less extent, the time when other traffic will have actually moved into their path, depending upon the differing degrees of their impatience upon various occasions, so that there comes an occasion when they reach the crossing or point of intersection at the very time it is occupied by another, while traveling at an especially rapid rate, thus intensifying the seriousness of the consequences.

If the development of such situations is to be prevented, it appears indispensable that when a highway traffic signal displays such a "stop" aspect, all approaching vehicles shall be required to stop short of it. However, in order to make it possible for the drivers of vehicles to do this, it is essential that warning shall be given them for a time in advance of the display of the stop

indication which is sufficient for them to arrest their movement before they reach the signal; and it is, of course, equally essential that such warning shall be of a kind which is calculated to be understood by all drivers having ordinary comprehension of the significance of the various aspects of highway traffic signals.

It is a further object to provide a traffic control signal display which flashes either a "stop" or a "go" signal for intervals of progressively decreasing duration and/or for durations separated by intervals of extinguishment of progressively decreasing duration.

In instances wherein a signal is flashed with progressively decreasing durations of the intervals between flashes, the durations of the displays themselves being substantially unchanged, a resulting characteristic signal display is obtained which gives an opposite visual impression from that given in instances wherein durations of the flashes are progressively decreased and the durations of the intervals between flashes are held either substantially constant or are also progressively decreased.

In the first instance the ratio of duration of intermittent signal display with relation to the duration the intervals between such displays, increases so that the display approaches a continuous one.

Such increased ratio has a very desirable effect on the movements of traffic when such intermittent display applies to the red or "stop" signal.

For example, the driver of a vehicle approaching an intersection and observing a flashing red signal, with the red display seemingly becoming more and more prominent, is not only psychologically urged to be on the alert for a change in signals, but is also given what might well be termed "a subconscious suggestion" that he should bring his vehicle to a stop even though he knows the green signal may persist long enough for him to get across.

As a result of such urge, drivers of vehicles are more likely to retard their speed at intersections and not attempt to "beat the light".

Furthermore, when the green or "go" light is flashed in accordance with the second instance, i. e., with the durations of flashes progressively decreased either with or without decreases in the durations of intervals between such flashes, another desirable psychological urge is presented which tends to cause drivers to stop their vehicles due to the decrease in the amount of display of the "go" signal. As a result of the tendency just

set forth, drivers of vehicles are deterred from attempts to "beat the light".

It is, therefore, a general object of this invention to provide a signaling system and mechanism therefor whereby a warning will be given when the signaling aspect is about to change, and in which such warning will be given by intermittently displaying or indicating a signaling aspect about to become effective.

10 It is a more specific object of this invention to display such a warning in a manner which will progressively indicate the increasing proximity of the time when the impending change will become effective.

15 Further objects are to provide embodiments of this invention which may be inexpensively produced, which will be durable, readily understood and will require a minimum of attention for purposes of maintenance, and which facilitate utilization of existing installations with a minimum of revision and extension.

20 For better understanding of this invention, reference may be had to the annexed drawings and the detailed descriptions thereof hereinafter contained, in which certain embodiments of this invention are illustratively indicated; however, it should be understood that although the embodiments so indicated are practical, they are by no means the only ones which this invention may 25 assume, and they are given without intent to imply limitation to the particular details and arrangements therein shown, except insofar as such details and arrangements are defined in the appended claims.

30 Similar reference characters indicate corresponding parts in the accompanying drawings, in which

35 Figure 1 diagrammatically indicates a simplified form of so-called "pre-timed" highway traffic 40 signaling equipment, embodying an aspect of this invention;

45 Fig. 2 correspondingly indicates the manner of applying another aspect of this invention to such a system;

50 Fig. 3 similarly indicates another embodiment of this invention for supplying results corresponding to those afforded by the system of Fig. 2;

55 Fig. 4 is a chart indicating the relative duration and times of occurrence of the color periods incident to a cycle of the operation of the system indicated by Figs. 1, 2 and 3;

60 Fig. 5 indicates the application of this invention to signaling equipment suited for response to vehicle or pedestrian movements and/or subject to coordination of activity with other signaling equipment; and

65 Figs. 6, 7, 8 and 9 are charts indicating the relative duration and times of occurrence of color periods which may be provided, in accordance with this invention, by revision of the movement, formation, arrangement and manner of connecting the cams and contacts of Figs. 1, 2, 3 or 5.

70 Referring to Fig. 1, a so-called "traffic signal controller" is generally indicated at C¹, and a group of signal lights situated at a highway intersection is correspondingly indicated at S¹.

75 The controller indicated at C¹ is illustrative of any one of various well-known types of traffic signal controllers which comprise circuit controlling mechanism and actuating means therefor. In this schematic illustration, the actuating means is exemplified by the motor 21¹, which acts through the gears 22¹ and 23¹ to drive the shaft 24¹; and the circuit controlling mechanism is

exemplified by the cams 31¹, 32¹, 33¹ and 34¹ which are driven by the shaft 24¹, and the pairs of circuit controller contacts 41¹, 42¹, 43¹ and 44¹ which are operatively associated with said cams, respectively.

75 The signal lights R^{m1}, R^{m1}, G^{m1}, G^{m1}, are provided for governing the movement of traffic which approaches the intersection along the vertically disposed one of the indicated highways which, for convenience, is designated by the word "Main" 10 and the lights R^{c1}, R^{c1}, G^{c1}, G^{c1}, are provided for governing the movement of traffic which approaches the intersection along the other of the indicated highways which, for convenience, is designated by the word "Cross".

15 It will be understood by those skilled in this art that the controller C¹ may include facilities whereby adjustments may be readily effected of the time intervals which intervene between recurrences of given signaling aspects in the cycle 20 of the operation of the controller as well as in the relative proportions of such cycle time which are allotted to one and the other of the alternate signal manifestations, for coördinating the activities of two or more of such controllers, 25 for rendering the controller responsive to traffic movements in one or more of the affected traffic channels, and for controlling and regulating traffic movements at intersections involving more than two highways or thoroughfares, besides providing facilities for meeting other of the multifarious situations presented by the various phases 30 of traffic control problems; however, such facilities are here omitted in the interest of simplicity and clearness, as it is believed that those skilled in this art are familiar with expedients whereby such characteristics may be readily associated to a needful extent in a controller embodying the aspect of this invention to which Fig. 1 is particularly directed.

35 The conductors 51¹ and 52¹ connect the motor 21¹ with the power supply; the conductor 53¹ connects conductor 52¹ with one terminal of each of the lamps R^{m1}, R^{m1}, R^{c1}, R^{c1}, G^{m1}, G^{m1}, G^{c1}, G^{c1}; the conductor 54¹ connects the conductor 51¹ with 40 one of the contacts of each of the pairs of circuit controller contacts 41¹, 42¹, 43¹ and 44¹; the conductor 55¹ connects the other of the pair 41¹ of circuit controller contacts with the lamps R^{m1}, R^{m1}; and the conductors 56¹, 57¹ and 58¹ 45 correspondingly connect the remaining contacts of the pairs 42¹, 43¹ and 44¹ with the lamps R^{c1}, R^{c1}, G^{m1}, G^{m1}; and G^{c1}, G^{c1};—respectively.

50 The cam 31¹ is so formed as to continuously permit closure of the contacts 41¹ during approximately one-half of each revolution of the shaft 24¹, and the cam 32¹ is so formed as to permit continuous closure of contacts 42¹ during the remainder of each revolution of the shaft 24¹. The cam 33¹ is so formed as to cause continuous separation of the contacts 43¹ throughout all of that half of each revolution of the shaft 24¹ during which cam 31¹ permits continuous closure of the contacts 41¹, and the cam 34¹ is so formed as to cause continuous separation of the contacts 44¹ 55 throughout all of the other half of each revolution of the shaft 24¹.

55 From the foregoing it will be apparent that during approximately one-half of each revolution of the shaft 24¹, the contacts 43¹ will be continuously closed, thus causing the lamps G^{m1}, G^{m1}, to be lighted and to thereby provide a "go" signaling aspect for the traffic approaching the intersection along the "Main" thoroughfare; and that, during the remainder of each revolution of 60

the shaft 24¹, the contacts 44¹ will be closed so that the lamps G^{c1}, G^{c1} will be lighted, to thereby provide a "go" signal for traffic approaching the intersection along the "Cross" thoroughfare. It will further be evident that so long as contacts 43¹ are closed, contacts 42¹ will also be closed, thereby providing a "stop" signal for traffic approaching the intersection along the "Cross" thoroughfare throughout the time that a "go" signal is provided for traffic approaching the intersection along the "Main" thoroughfare; and, correspondingly, whenever contacts 44¹ are closed, contacts 41¹ will also be closed, thereby correspondingly providing a "stop" signal for traffic approaching the intersection along the "Main" thoroughfare throughout the time that a "go" signal is provided for traffic approaching the intersection along the "Cross" thoroughfare.

A group of teeth 311¹ is formed in the periphery of cam 31¹ in such position that they will be carried past the co-engaging one of the contacts 41¹ just after the main or continuously raised portion of said cam 31¹ has withdrawn therefrom incidental to counter-clockwise rotation of said cam, to the end that when the contacts 41¹ have been held continuously open by the main raised portion of the cam 31¹, and while the cut-away portion of the cam 33¹ is still being presented to the contacts 43¹, the notches between the teeth 311¹ will permit a series of closures of the contacts 41¹, so that the red or "stop" signal lamps R^{m1}, R^{m1} will repeatedly flash just prior to the extinguishment of the green or "go" signal lamps G^{m1}, G^{m1}, and just prior to the continuous lighting of the lamps R^{m1}, R^{m1} which occurs while the cut-away portion of cam 31¹ is presented to contacts 41¹.

A similar group of teeth 321¹ is formed in the periphery of cam 32¹ for like actuation of contacts 42¹, so that the lamps R^{c1}, R^{c1} will be caused to repeatedly flash during burning and just prior to extinguishment of the lamps G^{c1}, G^{c1}.

The times of the occurrences of changes in the signaling aspects effected by the lighting and extinguishing of the signal lamps, with relation to the contours of the cams, is further illustrated by the chart of Fig. 4, which is representative of one revolution of shaft 24¹, and hence one cycle of the operation of the mechanism.

In this chart, the upper band RR^m is representative of the red lamps R^{m1}, R^{m1} of Fig. 1, and the band directly below same marked GG^m is representative of the green lamps G^{m1}, G^{m1}, all of which lamps are provided for controlling the movements of "Main" highway traffic.

The shaded portions of these bands indicate the times during the cycle when the lamps of the represented group are lighted, and the blank portions of these bands represent the times when these lamps are extinguished.

The line 310 is a development along a horizontal plane of the periphery of the cam 31¹, and the line 330 is a corresponding development of the periphery of the cam 33¹.

The bands RR^c and GG^c correspondingly represent the lamps R^{c1}, R^{c1}, and G^{c1}, G^{c1}, of Fig. 1, and the associated lines 320 and 340 correspondingly represent the peripheries of cams 32¹ and 34¹ of Fig. 1.

The operation of the system of Fig. 1 is as follows:

Upon application of a suitable source of power supply to the conductors 51¹ and 52¹, the motor 21¹ will run and, through the action of the reduction gearing 22¹, 23¹ will cause rotation of the

shaft 24¹ at the desired speed, so that the time occupied by each revolution of this shaft will be that desired for a cycle of signaling aspects.

Assuming that, at the time of the application of electrical energy to the conductors 51¹ and 52¹, the shaft 24¹ is so positioned that the raised portions of cams 31¹ and 34¹ have just been withdrawn from their associated contacts, the lamps R^{m1}, R^{m1} will be lighted, thus providing a "stop" aspect to traffic approaching the intersection 10 along the "Main" thoroughfare, and the lamps G^{c1}, G^{c1} will be lighted, thus providing a "go" aspect to traffic approaching the intersection along the "Cross" thoroughfare.

With cams formed as shown in Fig. 1, such aspects will continue for approximately one-half of a revolution of the shaft 24¹. However, during the latter portion of such half revolution, contacts 42¹ will be permitted to momentarily close through presentation of the notch between the continuous raised portion of cam 32¹ and the first of the teeth 321¹, whereupon the lamps R^{c1}, R^{c1} will be lighted. When the shaft 24¹ is thereupon rotated for a slight additional distance, the first of the teeth of the group 321¹ will cause separation of the contacts 42¹ and consequent extinguishment of the lamps R^{c1}, R^{c1}. This action will be repeated as the notches between the others of the teeth of the group 321¹ are presented to the contacts 42¹.

Through the resultant flashing of the lamps R^{c1}, R^{c1}, drivers of vehicles approaching the intersection along the "Cross" thoroughfare, who would otherwise reach and fail to clear the intersection after a "go" signaling aspect had been given to "Main" thoroughfare traffic, will be given 35 warning preceding the impending signal change by a time such that they will have opportunity to stop their vehicles before reaching the intersection.

As the last of the teeth of the group 321¹ is 40 withdrawn from the path of the co-engaging one of the contacts 42¹, the raised portion of the cam 34¹ will cause separation of the contacts 44¹, so that lamps G^{c1}, G^{c1} will be extinguished at the commencement of the interval during which 45 lamps R^{c1}, R^{c1} are continuously lighted. At the same time, the raised portion of cam 33¹ will be withdrawn from the co-engaging one of the contacts 43¹, and the raised portion of the cam 31¹ will cause separation of the contacts 41¹, thereby 50 causing the lighting of the lamps G^{m1}, G^{m1} and the extinguishment of the lamps R^{m1}, R^{m1}. Thus there will be provided a "stop" signaling aspect for traffic approaching the intersection along the "Cross" thoroughfare and a "go" signaling aspect for traffic on the "Main" thoroughfare.

Thereafter, during further rotation of the shaft 24¹, the signaling aspect just described will continue until the notch preceding the first of the teeth of the group 311¹ permits closure of the contacts 41¹, whereupon the lamps R^{m1}, R^{m1} will be flashed, and a warning signal will be given for traffic approaching the intersection along the "Main" thoroughfare corresponding to that already described as resulting from the actuation of contacts 42¹ by the notches between the teeth of the group 321¹.

When the last of the teeth 311¹ has been thus withdrawn from the path and thereby permitted 70 closure of the co-engaging one of the contacts 41¹, the lamps R^{m1}, R^{m1} will be continuously lighted; the raised portion of the cam 33¹ will cause extinguishment of the lamps G^{m1}, G^{m1} by separating the contacts 43¹; the raised portion of 75

the cam 34¹ will be withdrawn from the co-engaging one of the contacts 44¹, thereby causing lighting of the lamps G^{c1}, G^{c1}; and the raised portion of the cam 32¹ will cause separation of the contacts 42¹, so that lamps R^{c1}, R^{c1} will be extinguished. Thus there will be provided a "stop" signaling aspect for traffic approaching the intersection along the "Main" thoroughfare and a "go" signaling aspect for traffic on the "Cross" thoroughfare.

If, for any reason, it is desired to provide such a flashing signal for warning the traffic approaching along one of the highways, without providing a corresponding signal for traffic approaching 15 along the other highway, a continuation of the raised portion may be substituted for one or the other of the groups of teeth 321¹, 311¹.

It is evident from the foregoing, that, as indicated by the chart of Fig. 4, the warning flashes 20 resultant from operation of a system such as that of Fig. 1, and all the intervals therebetween, will be of substantially uniform durations, respectively. However, it is believed to be distinctly 25 advantageous to provide a larger number of flashes for such a warning signal, than can (for reasons believed to be well understood by those skilled in this art) be readily provided for with an arrangement such as is indicated by Fig. 1, and it is further desirable to cause such flashes to 30 occur at a progressively increasing rate, or, in other words, with progressively decreasing intervals therebetween.

The arrangement diagrammatically indicated by Fig. 2 accomplishes the result of thus progressively decreasing the interval between the flashes of each group, as well as increasing the 35 number of flashes in the group, while permitting a construction as compact and sturdy as that indicated by Fig. 1.

40 The lamps R^{m2}, R^{m2}, G^{m2}, G^{m2}, R^{c2}, R^{c2}, G^{c2}, G^{c2}, of Fig. 2, correspond to the similarly designated lamps of Fig. 1.

In the controller C² of Fig. 2, the motor 21², the reducing gearing represented by 22², 23², the 45 shaft 24², the cams 33² and 34², the contacts 41², 42², 43² and 44², and the conductors 51² and 58², inclusive, correspond with similarly indicated parts of Fig. 1.

50 The cams 31² and 32² are similar in contour to the cams 31¹ and 32¹, other than in that continuations of the raised portions are substituted for the groups of teeth 311¹ and 321¹, respectively. The cam 31² carries a pin 312² and the cam 32² carries a pin 322², the purposes of which 55 pins will be hereinafter more fully explained.

The cam 35 is fixed upon the shaft 24² and cooperates with the contacts 45 and 46 so that, during substantially one-half of each revolution of said shaft, the cam 35 will permit closure of 60 the contacts 45 and hold the contacts 46 open, and throughout a corresponding portion of the other half of each revolution of said shaft said cam will permit the closure of the contacts 46 and hold contacts 45 open.

65 An auxiliary shaft 61² has the pinions 62 and 63, and the ratchet wheel 64 fixed thereon, and the toothed wheel 65² is loosely journaled upon said shaft. The ratchet dog 67 is pivotally mounted upon the wheel 65², the free end of said 70 dog being urged into engagement with the teeth of ratchet wheel 64 by the spring 68.

The contact 71² is tensioned for movement toward, and the free end thereof is disposed in the path of the teeth of the wheel 65², so that, 75 upon rotation of said wheel, said contact will be

moved into and out of engagement with the contact 72².

The teeth of the wheel 65² vary in pitch from widely spaced teeth such as the teeth 73 and 74, to closely spaced teeth such as the teeth 75 and 76; so that, upon counter-clockwise rotation of said wheel at substantially uniform rate, from the position where tooth 73 engages contact 71² to that in which tooth 76 engages said contact, the intervals between engagements of adjacent ones of said teeth will be of progressively decreasing duration.

The conductor 81 connects contact 71² with conductor 54²; the conductor 82 connects contact 72² with one of the contacts 46; conductor 83 connects conductor 82 with one of the contacts 45; conductor 84 connects the other one of the contacts 46 with conductor 56²; and conductor 85 connects the other of the contacts 45 with conductor 55².

The rack bars 91² and 92² engage the pinions 62 and 63, respectively; these bars being supported by studs 94², 94², 94², 94², which project through slots 95 permitting lengthwise movement of said bars while engaging their respective pinions, for imparting desired rotation to the auxiliary shaft 61². Inasmuch as the bars 91² and 92² are interconnected through the shaft 61² and their associated pinions 62 and 63, respectively, each will respond to actuation of the other.

The springs 96², 96² are applied to the bars 91² and 92² for lifting them to the limit of movement permitted by their supporting studs 94², and the upper ends 97, 97, of said rack bars extend into the paths of the pins 312² and 322², respectively, so that, when the shaft 24² is rotated by the motor 21², the pins 312² and 322² will each, one after the other, engage and then disengage its respective rack bar, thereby effecting simultaneous movement of said rack bars against the tension of their associated springs 96², 96². The arrangement of said bars 91² and 92², with relation to the paths of movement of said pins 312² and 322², respectively, is such that, when one or the other of said pins engages its associated rack bar, it will move same to an extent such as will cause one revolution of the auxiliary shaft 61² and will then move out of the path of the cooperating end 97 of such bar, whereupon the parts 55 will be returned to their normal position by the springs 96², 96².

The pin 312² is so situated with relation to the raised portion of the cam 31², that said pin will engage the bar 91² during intended counter-clockwise rotation of the shaft 24², sufficiently in advance of the withdrawal of the raised portion of said cam from engagement with the contacts 41², that the resultant rotation of the auxiliary shaft 61² will have been completed just before the raised portion of the cam 31² is withdrawn to thereby permit the contacts 41² to close. The pin 322² is correspondingly located with reference to the raised portion of cam 32².

The cam 35 is so positioned upon the shaft 24² as to permit closure of the contacts 45 through 65 out actuation of the rack bar 91² by the pin 312², and so as to permit closure of the contacts 46 throughout actuation of the rack bar 92² by the pin 322².

The operation of the system of Fig. 2 is as 70 follows:

Upon application of a suitable source of power supply to the conductors 51² and 52², the motor 21² will act through the gearing 22², 23² to drive the shaft 24², and thereby rotate the cams 31², 75

- 32¹, 33¹, 34¹ and 35¹. The resulting lighting and extinguishment of the lamps of signal S¹ will correspond to that hereinbefore described in connection with Fig. 1, insofar as the continuous lighting and extinguishment of said lamps is concerned; however, the flashing of the red lamps shortly before the extinguishment of their associated green lamps is accomplished in a distinctly different manner, as will now be described.
- 10 Assuming that the cam 33² has permitted the contacts 43² to remain closed until a time when the "Main" thoroughfare red lamps R^{m2}, R^{m2} should commence flashing, the pin 312² will be carried into engagement with the upper end 97 of the bar 91², so that the continued rotation of shaft 24² will cause said bar to move downwardly in engagement with pinion 62, and thereby rotate shaft 61².
- 15 Such rotation of shaft 61² will cause ratchet wheel 64 to drive wheel 65², acting through ratchet dog 67, in a counter-clockwise direction, thereby consecutively bringing the teeth of wheel 65² into engagement with contact 71², so as to repeatedly move same into engagement with contact 72². Throughout such rotation of wheel 65², the cam 35 will permit closure of the contacts 45; the various parts being shown in Fig. 2, as positioned approximately midway the rotation of shaft 61² responsive to the movement of rack bar 91² by pin 312². Upon each closure of the contacts 71² and 72², a current path will be established from conductor 51², through conductor 54², conductor 81, contacts 71² and 72², conductors 82 and 83, contacts 45, conductor 85, conductor 55², red lamps R^{m2}, R^{m2}, conductor 53² to conductor 52². It is therefore evident that the lamps R^{m2}, R^{m2} will be briefly lighted or "flashed" during the successive engagements of the various teeth of the wheel 65², and that, during the rotation of such wheel, the intervals between such flashes will progressively decrease, due to the progressive decrease in the spacings between such teeth. It will also be evident that the durations of the flashes will be substantially uniform.
- 20 Following the disengagement of tooth 76 from contact 71², pin 312² will be carried by cam 31² out of the path of the upper end 97 of bar 91², whereupon springs 96², 96² will act through bars 91² and 92² to cause clockwise rotation of shaft 61² to an extent corresponding to the counter-clockwise rotation imparted to said shaft through actuation of the bar 91² by the pin 312².
- 25 The wheel 65² will not rotate with the shaft 61² during such clockwise movement, being permitted by the dog 67 to remain in the position where the contact 71² rests between the teeth 76 and 73, contact 71² thus being out of engagement with contact 72².
- 30 Immediately following the termination of the counter-clockwise rotation of the wheel 65², the rise of the cam 33² will act to separate contacts 43² and thus cause extinguishment of lights G^{m2}, G^{m2}, and the rise of cam 31² will be withdrawn so as to permit contacts 41² to close and thereby effect continuous lighting of the lamps R^{m2}, R^{m2}, whereby a "stop" signaling aspect is given to traffic approaching the intersection along the "Main" thoroughfare. At substantially the same time, the rise of cam 32² will effect separation of contacts 42² and thus extinguish lamps R^{c2}, R^{c2}, and the rise of cam 34² will be withdrawn and thereby permit closure of contacts 44², and thus cause lighting of the lamps
- 35 G^{c2}, G^{c2}, so as to provide a "go" signaling aspect for the "Cross" thoroughfare.
- 40 In the course of subsequent rotation of the shaft 24², the rise of cam 35 will effect separation of contacts 45, and will be withdrawn and permit closure of contacts 46; after which, in suitable timed relation prior to release and consequent closure of contacts 43² and 42² by cams 33² and 32², respectively, pin 322², carried by said cam 32², will engage the upper end 97 of bar 92², and thereby cause rotation of shaft 61² and resultant operation of contact 71² as hereinbefore more fully explained.
- 45 During such operation of contact 71², resultant from engagement of pin 322² with the upper end 97 of bar 92², each time that said contact 71² is pressed against contact 72² a current path will be established from conductor 51², through conductors 54² and 81, contacts 71² and 72², conductor 82, contacts 46, conductors 84 and 56², through lamps R^{c2}, R^{c2}, and conductor 53² to conductor 52²; thereby causing the lamps R^{c2}, R^{c2}, to be flashed during the engagement of each of the teeth of the wheel 65², as hereinbefore more fully described.
- 50 From the foregoing, it will be evident that the general results of the operation of a signaling system arranged in accordance with Fig. 2 is substantially the same as is indicated in the chart in the upper portion of Fig. 4, except that the red flashes will be more numerous, and will be separated by intervals of progressively decreasing duration, as exemplified by the band 2, of the chart of Fig. 4 which shows the uniformity of duration of the flashes and the progressive decrease of the spaces therebetween, the time interval represented by these bands being equivalent to that embraced between the lines a, b as they intersect the bands RR^m, GG^m, RR^c and GG^c of this chart.
- 55 Referring next to Fig. 3, it will be observed that there is here disclosed an arrangement for operating a pair of flashing contacts 71³ and 72³ from a wheel 65³ which differs in a number of respects from the arrangement of Fig. 2.
- 60 The cams 31³ and 32³ are associated with contacts 41³ and 42³, and are fixed upon the shaft 24³. It should be understood that contacts corresponding to 43², 44², 45 and 46 of Fig. 2, or structure providing equivalent functions, should be made operative incidental to rotation of the shaft 24³.
- 65 The pins 312³ and 322³ are carried by the cams 31³ and 32³ for cooperation with the levers 91³ and 92³ so that, as the shaft 24³ revolves, said levers will be successively engaged by said pins and thereby swung through a predetermined path.
- 70 The levers 91³ and 92³ are pivoted at 94³, 94³ in comparatively close proximity to the paths of the pins 312³ and 322³, respectively; and the free ends of the portions of said levers which extend from their pivots away from the paths of said pins have secured thereto flexible members or straps 101, 102 which extend around and are secured to the cam shaped members 103, 104 which are fixed upon the sleeves 36 and 37, respectively, which sleeves are loosely journaled upon the shaft 61³.
- 75 The springs 96³, 96³ are so applied to the cams 103, 104 as to resiliently oppose rotation imparted thereto when the pins 312³ and 322³ act, one after the other, to swing their associated levers 91³ and 92³.
- 80 The discs 105 and 106 are fixed upon the sleeves 75

36 and 37, respectively; and, hence, are journaled upon the shaft 61³ and rotate with the cams 103 and 104, respectively.

The ratchet wheels 107 and 108 and the wheel 65³ are fixed upon the shaft 61³, and the ratchet wheel 107 is connected with the disc 105 through the ratchet dog 109, so that when the pin 312³, acting through the lever 91³ and strap 101 causes rotation of the member 103, the wheel 65³ will be caused to rotate therewith; but when the member 103 is rotated in the opposite direction in response to its spring 96³, the dog 109 will permit the wheel 65³ to remain unaffected thereby. A corresponding connection (not shown) enables the disc 106 to drive ratchet wheel 108.

The peripheries of the cam members 103 and 104 are of such contour that the movement imparted to the levers 91³ and 92³ by their respectively associated pins 312³ and 322³ will cause rotation of their associated cams at a progressively increasing speed. As the teeth of the wheel 65³ are all of the same pitch, it will therefore be evident that the rotation of said wheel, resultant from the rotation of the shaft 24³, will be at a progressively increasing speed, so that the flashes of the signal lamps caused by the actuation of the contacts 71³ and 72³ which result from such rotation of wheel 65³ will be of durations and will be separated by intervals both of which will progressively decrease, as indicated by the band 3 of the chart of Fig. 4.

Referring next to the arrangement diagrammatically indicated by Fig. 5, it will be observed that a signaling system embodying the structural characteristics there indicated is suited for response to vehicle or pedestrian movements as well as being suited to coördination of activity with other signaling equipment.

As in the instances of Figs. 2 and 3, certain of the equipment indicated by Fig. 5 substantially corresponds in structure and function with similar parts which are hereinbefore described in detail, and it is therefore deemed unnecessary to here repeat such description.

The shaft 24⁵ which is driven by the motor 21⁵, through suitable reduction gearing 22⁵, 23⁵, drives cams 201, 202, 203, 204 and 205, in suitable angular relationships to cams 31⁵, 32⁵, 33⁵ and 34⁵; which latter cams substantially correspond with cams 31¹, 32¹, 33¹ and 34¹ of Fig. 1.

The contacts 211, 212, 213, 214 and 215 are associated with the cams 201, 202, 203, 204 and 205, respectively.

The periphery of cam 201 is so formed as to permit closure of contacts 211 during those portions of each revolution of the shaft 24⁵ when the teeth 311⁵ and 321⁵ of the cams 31⁵ and 32⁵ are being carried past the contacts 41⁵ and 42⁵, respectively. The periphery of cam 202 is so formed as to effect separation of contacts 212 during and substantially throughout each closure of contacts 211, as permitted by cam 201, and for further effecting separation of contacts 212 during a portion of each occasion when cam 33⁵ permits closure of contacts 43⁵. The purposes of such controls of contacts 211 and 212 will be hereinafter more fully explained.

The periphery of cam 203 is so formed as to permit closure of contacts 213 just prior to that separation of contacts 212 which occurs during closure of contacts 43⁵. The periphery of cam 204 is so formed as to permit closure of contacts 214 throughout each revolution of shaft 24⁵, other than for a brief interval shortly after cam 34⁵ has permitted closure of contacts 44⁵; and the

periphery of cam 205 is so formed as to permit closure of contacts 215 only during the early portion of that part of the revolution of shaft 24⁵ during which cam 31⁵ permits continuous closure of contacts 41⁵, for reasons which will be herein-after more fully explained.

It will be understood by those skilled in this art that adjustment may be effected of the relative durations of those portions of the operative cycle which are permissive for traffic movements along the "Main" and "Cross" thoroughfares by varying the angular extent of the raised portions of cams 33⁵ and 34⁵, and of the solid raised portions of the cams 31⁵ and 32⁵, through the utilization of well-known expedients. The presence of facilities for effecting such adjustments is diagrammatically represented by the pointer handle 221 and the associated bars 222, 222.

Associated with the controller C⁵ just described, there is provided a relay having a magnet 231, together with sets of contacts 232 and 233; an adaptation switch 250; a flasher 234, which may be of any well-known and commercially available type having facilities for effecting intermittent interruptions of current flow therethrough as, for example, a so-called "thermo-flasher"; and traffic responsive equipment comprising a transformer having a primary winding 241, a secondary winding 242, an associated bridge rectifier 243, a relay having a winding 244 supplied through said rectifier, to control the set of contacts 245 and move the contact 247 into engagement with the contact 246 and thereby force it away from contact 248.

Signal lamps situated at the highway intersection S⁵ are responsively connected with the controller C⁵, and the so-called "master controller" shown at M is provided for coordinating the operation of the local controller C⁵ with that of other local controllers. It will, however, be readily understood that a local controller, such as C⁵, may be operated independently of any master controller, as will be hereinafter more fully explained.

The master controller M comprises a motor 260 which acts through suitable reduction gearing 261 and 262, to drive the disc or cam 263, for controlling the pair of contacts 264 in such manner that said contacts will be caused or permitted to close for a suitable and preferably brief interval during each revolution of said disc.

An adjustable resistance 265 affords facilities for effecting variations in the speed of the operation of motor 260, and a second adjustable resistor 266 is provided for effecting variations in the speed of the motors of associated local controllers, as will be hereinafter more fully explained.

The double pole three-way switch 250 comprises the arms 251 and 252, the contacts 253, 254 and 255 associated with arm 251, and the contacts 256, 257 and 258 associated with arm 252; the arms 251 and 252 being connected by the insulating link 259 for simultaneous movement, for purposes which will be hereinafter more fully explained.

The conductors 401, 402 convey energy from a suitable source of electric power supply to the signal lamps provided at the highway intersection S⁵ and to the transformer primary winding 241, through conductors as follows: conductor 403 connects conductor 401 with one terminal each of the amber signal lamps A^c, A^c, A^m, A^m; conductor 404 connects conductor 401 with one of the contacts 232, and conductor 405 connects

the other of said contacts with one of the terminals of each of all of the remaining signal lamps. Conductor 406 connects conductor 401 with one terminal of transformer primary winding 241 and conductor 407 connects the other terminal of said winding to conductor 402. Conductor 408 connects conductor 402 to one of the contacts of each of the pairs 215, 41⁵, 42⁵, 43⁵ and 44⁵ and, through a flasher 234 to one of the contacts of pair 233; the other contact of said pair being connected through conductor 409 with the remaining terminals of amber lamps A^c, A^c, A^m, A^m, and the remaining contact of the pair 215. Conductor 55⁵ connects the remaining one of the contacts of the pair 41⁵ with the remaining terminals of the "Main" thoroughfare red lamps R^{m₅}, R^{m₅}, and the conductors 56⁵, 57⁵ and 58⁵ correspondingly connect the remaining contacts of the pairs 42⁵, 43⁵ and 44⁵ with the remaining terminals of the "Cross" thoroughfare red lamps R^{c₅}, R^{c₅}, the "Main" thoroughfare green lamps G^{m₅}, G^{m₅}, and the "Cross" thoroughfare green lamps G^{c₅}, G^{c₅}, respectively.

The conductors 421 and 422 supply power from a suitable source to the master controller M, and electrical connections are provided within said controller as follows: conductor 431, which serially includes adjustable resistor 265, connects supply conductor 421 with one terminal of motor 260, and conductor 432 connects the other terminal of said motor to conductor 422. One terminal of adjustable resistor 266 is connected to conductor 421, and conductor 433 connects the other terminal of said resistor with terminal 442 of local controller C⁵. Conductor 434 connects conductor 422 with terminal 441 of the local controller, and conductors 435 and 436 connect the respective contacts of the pair 264 with terminal 443 of said local controller and supply conductor 421, respectively. Conductor 437 connects supply conductor 421 with terminal 444 of said local controller C⁵.

It will be understood that conductors 421 and 422 may be connected with the same source of electrical energy as conductors 401 and 402, or to a different source, as convenience may require.

Conductors are provided in local controller C⁵, in association with terminals 441, 442, 443 and 444 thereof, as follows: conductor 451 connects terminal 441 to one terminal of the motor 21⁵, and conductor 452 connects the other terminal of said motor directly with one of the contacts of each of the pairs 212 and 213, and serially through adjustable resistor 453 with one of the contacts of pair 211; conductor 454 connects conductor 451 with one end of relay winding 231, and the other end of said winding is connected through conductor 455 to an end of conductor 456, the other end of said conductor 456 being connected to terminal 444; conductor 457 connects conductor 456 to the remaining terminal of pair 211; terminal 442 is connected to contact 256 of switch 250 through conductor 458 and through conductor 450 to the other of the contacts of pair 212; and conductor 459 connects contact 254 of said switch to terminal 443; said contact 254 being also connected, through conductor 460 to contact 258 of said switch.

Dotted lines are shown proceeding from terminals 441, 442, 443 and 444, which lines are representative of conductors which may be supplied for correspondingly connecting similar terminals of other local controllers.

One of the relay contacts 245 is connected

through conductor 461 with switch arm 251 and is also connected through conductor 462 with the remaining one of the contacts 213; the other one of the pair 245 of relay contacts is connected through conductor 463 with switch arm 252.

One end of transformer secondary winding 242 is connected through conductor 464 with traffic responsive circuit controllers TRC, TRC which are situated in the path of traffic approaching the intersection along the "Cross" thoroughfare. The other end of transformer secondary winding 242 is connected through conductor 465 to one of the alternating current input terminals of bridge rectifier 243, the other A. C. input terminal of said rectifier is connected through conductor 466 to relay contact 246. Relay contact 247 is connected through conductor 467 to one of the pair of contacts 214, and the other contact of said pair is connected to the intermediate terminal of transformer secondary 242 through conductor 468. Conductor 469 connects relay terminal 248 with remaining terminals of traffic responsive circuit controllers TRC, TRC. Conductors 470 and 471 connect the ends of relay winding 244 with the D. C. output terminals of bridge rectifier 243, respectively.

Relay contacts 232 are so associated with winding 231 as to be closed responsive to effective energization of said winding; and contacts 233 are so associated as to be open during such energization.

Contacts 245 are so associated with relay winding 244 as to be closed responsive to effective energization of said winding, and contact 247 is so associated as to be moved into engagement with contact 246 responsive to such energization and thereby causing the separation of contacts 246 and 248.

The operation of a system arranged in accordance with Fig. 5 is as follows:

Assuming that the arms 251 and 252 of adaptation switch 250 are resting upon contacts 253 and 256, respectively, and that suitable electrical energy is applied to conductors 401, 402, 421 and 422, the controller C⁵ will be rendered traffic responsive, and will operate independently of master controller M. Relay winding 231 will be energized through a current path extending from power supply, through conductors 421 and 437 to terminal 444, and thence through conductors 456 and 455 to one end of said winding; and thence through said winding and from the other end thereof through conductors 454 and 451 to terminal 441 and thence through conductors 434 and 422 to the power supply. The resultant energization of winding 231 will cause separation of contacts 233, and closure of contacts 232. Such closure of contacts 232 will complete a current path from the power supply through conductors 401 and 404, through contacts 232 and conductor 405 to one of the terminals of each of the signal lamps R^{m₅}, R^{m₅}, G^{m₅}, G^{m₅}, R^{c₅}, R^{c₅}, G^{c₅}, G^{c₅}.

When the parts responsive to rotation of shaft 245 are positioned as shown by the drawing, signal lamps R^{c₅}, R^{c₅} and G^{m₅}, G^{m₅} will be lighted, through current paths rendered effective at contacts 42⁵ and 43⁵ as hereinbefore more fully described, and motor 21⁵ will be energized through the establishment of a current path from the power supply through conductors 421 and 437 to terminal 444, thence through conductors 456 and 457, contacts 211, adjustable resistor 453, and conductor 452 to one terminal of motor 21⁵; and from the other terminal of said motor through

conductor 451 to terminal 441, and thence through conductors 434 and 422 to the power supply.

The energization of motor 215, through the current path just indicated, will cause rotation of the shaft 245, thereby bringing one after another of the notches between the teeth 311⁵ of cam 31⁵ into the path of the co-operating one of the contacts 41⁵, to thereby cause flashing of the signal lamps R^{m5}, R^{c5}, as hereinbefore more fully explained.

After the final one of the teeth 311⁵ has been thus withdrawn from the co-engaging one of the contacts 41⁵, said contacts will be and remain closed throughout approximately one-half of a revolution of the shaft 245. Upon rotation of the cam 31⁵ to the position which permits such continuous closure of the contacts 41⁵, cams 202 and 205 will have been moved to positions permitting closure of their associated contacts 212 and 215, respectively, and cam 33⁵ will have moved to a position where it separates contacts 43⁵; and, upon slight additional rotation thereafter, cam 201 will effect separation of its associated contacts 211.

Such closure of contacts 215 will cause lighting of the amber lamps A^m, A^m, A^c, A^c, through a current path as follows: from the power supply through conductors 401 and 403 to one of the terminals of each of said lamps, from the opposite terminals of said lamps through conductor 409, contacts 215, and conductors 408 and 402 to the power supply. The concurrent separation of contacts 43⁵ will cause extinguishment of signal lamps G^{m5}, G^{c5}. Because of the circuits and conditions thus established, red and amber signals will be given to all traffic which, pursuant to the rules effective in certain localities, establishes a so-called "pedestrian period" during which pedestrians may move freely across the intersection, and vehicles are forbidden entrance thereupon.

The closure of contacts 212 established a connection from power supply conductor 421 through adjustable resistor 266 and conductor 433 to terminal 442, thence through conductor 450 and contacts 212 to conductor 452; thus replacing the current path there interrupted at contacts 211, which path extends from power supply through conductors 421, and 437 to terminal 444, and thence through conductors 456 and 457, to and through contacts 211, and adjustable resistor 453 to conductor 452.

After the "pedestrian period" signaling aspect just described has been maintained for a desired time, the continued rotation of the shaft 245 will move the cams 205 and 32⁵ to positions where they separate their respectively associated contacts 215 and 42⁵, and the cam 34⁵ will thereupon have moved to a position where it permits closure of contacts 44⁵.

Such separation of contacts 215 and 42⁵ will cause extinguishment of all of the amber signal lamps and of the "Cross" thoroughfare red signal lamps, R^{c5}, R^{m5}, and such closure of contacts 44⁵ will cause lighting of the "Cross" thoroughfare green signal lamps G^{c5}, G^{m5}; since the "Main" thoroughfare red signal lamps R^{m5}, R^{c5} were previously lighted through continuous closing of contacts 41⁵, there is thus provided a "stop" aspect for traffic approaching the intersection along the "Main" thoroughfare and a "go" aspect for traffic approaching the intersection along the "Cross" thoroughfare. Shortly after the commencement of this signaling aspect, the con-

tinued rotation of shaft 245 will cause the raised portion of cam 204 to momentarily effect separation of its associated contacts 214, for a purpose which will be hereinafter more fully explained.

When such signaling aspects have been maintained for a desired time, the continued rotation of shaft 245 will withdraw the continuous raised portion of cam 32⁵ from contacts 42⁵, so that flashing of the lamps R^{c5}, R^{m5} will occur as the notches between teeth 321⁵ are presented to the co-engaging ones of contacts 42⁵, in the manner hereinbefore more fully explained. During such flashing of said lamps, the cam 201 will be so positioned as to permit closure of contacts 211, and the cam 202 will be so positioned as to effect separation of contacts 212, thereby placing the speed of operation of the motor 215 in control of the adjustable resistor 453, instead of the adjustable resistor 266.

From the foregoing it will be apparent that the speed of the motor 215 during the "red flashing periods" may be varied by adjustment of the resistor 453, so that the time occupied by such flashing periods will be in accordance with the practical conditions obtaining at the intersection S⁵, without thereby effecting the extent of the times during which traffic movements are permitted along the "Main" and "Cross" thoroughfares, respectively.

Immediately after the final one of the teeth 321⁵ has been withdrawn from the co-engaging one of the contacts 42⁵, the continued rotation of shaft 245 will carry cams 31⁵ and 34⁵ to positions where they will effect separation of their respectively associated contacts 41⁵ and 44⁵, and will carry cams 33⁵ to a position where it permits closure of contacts 43⁵; thereby causing a "stop" signaling aspect for "Cross" thoroughfare traffic and a "go" aspect for "Main" thoroughfare traffic, in the manner hereinbefore more fully explained.

Shortly after the establishment of signaling aspects as just referred to, cam 203 will reach a position where it permits closure of its associated contacts 213, and cam 202 will thereupon reach a position in which its raised portion 2021 will effect separation of contacts 212.

Such separation of contacts 212 will interrupt the current path theretofore supplying motor 215, and said motor will come to rest unless an alternate current path is established through contacts 213, in a manner which will be more fully described.

The traffic responsive circuit controllers indicated at TRC, TRC in the "Cross" thoroughfare near the intersection S⁵, may be of any well-known type providing facilities whereby pedestrians wishing to cross one of the thoroughfares at the intersection and/or vehicles approaching the intersection along the "Cross" thoroughfare, may effect closure of normally open contacts.

Upon closing the contacts of either of the circuit controllers TRC, TRC a current path is established from transformer secondary winding 242, through conductor 464, through the closed contacts of such circuit controller TRC, through conductor 469, contacts 248 and 246, and conductor 466 to one of the A. C. input terminals of bridge rectifier 243, and from the other input terminal of said rectifier through conductor 465 to the other end of transformer secondary winding 242. Current will thereupon flow through the path just indicated because of excitation of primary winding 241 from the power supply

through conductors 401 and 406 to one end of said winding 241, and from the other end of said winding through conductors 407 and 402 to the power supply.

5. The alternating current flow through bridge rectifier 243 resultant from closure of one of the circuit controllers TRC, TRC will cause direct current energization of relay winding 244, because of the connection of the ends of said winding through conductors 470 and 471 with the respective direct current output terminals of bridge rectifier 243.

Such energization of relay winding 244 will cause contact 247 to move into engagement with contact 246 and move the latter away from contact 248; and will, at the same time, cause contacts 245 to close.

When contact 247 is thus brought into engagement with contact 246, a so-called "lock-up" current path for relay winding 244 is established, which excludes a portion of transformer secondary winding 242 and conductor 464, controllers TRC, TRC as well as conductor 469 and contact 248. Thereupon, contact 246 is moved away from contact 248 thus discontinuing current flow through the path just traced, the resistance of said path being such that nothing objectionable will result from the momentary closure of the path which occurs when the contact 247 engages contacts 246, and before the latter contact has moved away from contact 248.

The "lock-up" current path just referred to is as follows: From an end of transformer secondary winding 242, through conductor 465 to one of the A. C. input terminals of bridge rectifier 243, and from the other A. C. terminal of said rectifier, through conductor 466, contacts 246 and 247, conductor 467, contacts 214 and conductor 468 to the intermediate terminal of transformer secondary winding 242; thereby effecting energization of relay winding 244, through the action of the rectifier 243, and the conductors 470 and 471.

If contacts 213 are closed at the time that contacts 245 are closed responsive to energization of winding 244, as just described, an energizing current path for motor 215 will be established from the power supply through conductor 421, adjustable resistor 266, conductor 433 to terminal 442, thence through conductor 458 to adaptation switch terminal 256, thence through arm 252, conductor 463, contacts 245, conductor 462 to contacts 213, thence through conductor 452 to one terminal of said motor. From the other terminal of the motor such current path leads through conductor 451 to terminal 441 and thence through conductors 434 and 422 to the power supply, thereby establishing a path which will cause starting and operation of motor 215. If, however, the contacts 213 are open at the time that contacts 245 are closed, operation of motor 215 will be maintained through the current path provided through conductor 452, contacts 212, and conductor 450 to the aforesaid terminal 442 until contacts 213 have closed, after which the operation of said motor 215 will be maintained through the current path including contacts 213, as just referred to, notwithstanding opening of contacts 212 by raised portion 2021 of cam 202, and the cycle of operation hereinbefore more fully explained will be repeated.

During such cycle of operation, and shortly after establishment of a signaling aspect permissible for vehicles approaching the intersection 75 along the "Cross" thoroughfare, the raised por-

tion of cam 204 will be brought into engagement with and cause separation of contacts 214, thereby interrupting the "lock-up" current path for relay winding 244; whereupon contacts 245 will be opened and contact 247 will move away from contact 246, permitting the latter to move into engagement with contact 248; whereupon, the ensuing rotation of shaft 245 will quickly withdraw the raised portion of cam 204 from contacts 214 permitting said contacts to close and thereby rendering the "lock-up" circuit effective for maintaining energization of winding 244 following the next succeeding closure of a contactor TRC.

Next assuming that the arms 251 and 252 of adaptation switch 250 are resting upon contacts 254 and 257, the controller C⁵ will be responsive to master controller M, and will operate independently of the circuit controllers TRC, TRC.

In other words, after the motor 215 has become deenergized, because of the separation of the contacts 211 by cam 201 and the concurrent separation of contacts 212 by the raised portion 2021 of cam 202, reenergization of said motor will be effected upon closure of contacts 264 of master controller M through a current path from power supply through conductors 421 and 436, through contacts 264, and conductor 435 to terminal 443; thence through conductor 459, contact 254, switch arm 251, conductor 461, conductor 462, closed contacts 213, and conductor 452 to a terminal of said motor.

During such operation, the resistors 265 and 266 should be so relatively adjusted that the speed of disc 263 will be somewhat less than that of shaft 245, in order that the motor 215 will become deenergized whenever the raised portion 2021 of cam 202 effects separation of contacts 212, and said motor 215 will be thereafter reenergized when the raised portion of cam 263 is withdrawn from contacts 264, permitting closure of said contacts.

It will be evident that if it is desired to lengthen the duration of the "go" signaling aspect for the "Main" thoroughfare, this can be accomplished by decreasing the speed of motor 260, through adjustment of resistor 265. If it is desired to increase the duration of "go" signaling aspect for the "Cross" thoroughfare, this can be accomplished by decreasing the speed of motor 215 by suitable adjustment of resistor 266; which change in speed will not, however, be effective during the "flashing red periods", as motor 215 is then supplied through adjustable resistor 453 instead of adjustable resistor 266 during such periods.

When the switch arms 251 and 252 of switch 250 are resting upon contacts 255 and 258, the controller C⁵ will be rendered responsive to actuation of contactors TRC, TRC only during closures of master controller contacts 264; so that, so long as said controllers TRC, TRC are not operated, a "go" signaling aspect may be given for traffic approaching the intersection along "Main" thoroughfare; and following actuation of either of said controllers TRC, TRC, energization of motor 215, and consequent rotation of shaft 245, will be initiated only at a time when contacts 264 of master controller M have closed; to the end that if a number of local controllers are associated with the master controller M, the controller C⁵ will effect discontinuance of the "go" signaling aspect for "Main" thoroughfare traffic only upon occasions which have intended

time, relation to the operation of master controller M.

From the foregoing it will also be apparent that, if the arms 251 and 252 are positioned as previously described upon contacts 253 and 256, the master controller M need not be supplied; in which event the adjustable resistor 266 may, if needed, be inserted between terminal 442 and conductors 450 and 458.

10 As previously explained, the relay winding 231 receives energization through a current path extending from power supply, through conductors 421 and 437 to terminal 444, and thence through conductors 456 and 455 to and through said winding, through conductors 454 and 451 to terminal 441, and thence through conductors 434 and 422 to power supply.

From the foregoing it will be apparent that in situations where conductors 401 and 402 are con-

20 nected to a power supply other than that which supplies conductors 421 and 422, failure of such supply to cause effective energization of relay winding 231, would permit contacts 232 to separate and contacts 233 to close.

25 Since, as previously explained, connection of the power supply to the lamps R^{m5} , R^{m5} , G^{m5} , G^{m5} , R^{c5} , R^{c5} , G^{c5} , G^{c5} is dependent upon closure of contacts 232, it will be evident that the separation of contacts 232 will cause the extinguishment of any of such lights which would otherwise be lighted throughout such time. Furthermore, the closure of contacts 233 causes the amber lamps A^m , A^m , A^c , A^c , to be lighted through the establishment of a current path as follows: from 30 power supply through conductors 401 and 403 to one terminal of each of said amber lamps, thence, through said lamps and from the remaining terminals thereof through conductor 409, contacts 233, conductor 408 and flasher 234 to 35 and through conductor 402 to the power supply.

40 The inclusion of flasher 234 in the current path just traced causes, in a well-known manner, an intermittent lighting or flashing of the amber lamps which, pursuant to the rules effective in 45 certain localities, establishes a so-called "caution" signal.

45 It will be apparent to those skilled in this art that various re-arrangements of cam periphery configurations, contacts and electrical connections may be made, pursuant to this invention so as to provide different signalling aspect cycle components such, for example, as are indicated by the charts of Figs. 6, 7, 8 and 9.

50 Fig. 6 is a chart indicating a cycle having a period in which a green or "go" signaling aspect is provided for "Main" thoroughfare traffic, during the latter portion of such period a flashing amber aspect is concurrently provided which is followed by a steady amber aspect which commences before the termination of the green aspect and persists for a short time thereafter and until the commencement of a steady red aspect; a corresponding cycle of color changes in reverse order being provided for the "Cross" thoroughfare.

55 The chart of Fig. 7 indicates a color cycle for each thoroughfare comprising a steady green portion which persists until the commencement of a steady red portion, a flashing green portion being provided concurrently with the early part of the red portion.

60 The chart of Fig. 8 shows a color cycle comprising a steady green portion, followed by a flashing green portion, which, in turn, is followed 65 by a steady red portion.

65 The chart of Fig. 9 indicates a cycle for each thoroughfare comprising a steady green portion during the latter part of which there is a flashing amber period followed by a steady amber period, and following the green portion there is a second flashing amber period followed by a steady amber period, following the termination of which there is a steady red portion.

70 Obviously, other structures may be devised which may embody the invention herein set forth. The drawings and description thereof are therefore to be considered in an illustrative and not in a limited sense; and it should be understood that the language used in the following claims is intended to cover all of the generic and specific 15 features of the invention herein described and all statements of the scope of the invention, which, as a matter of language, might be said to fall therebetween.

75 I claim:

1. In a signaling system, a source of electrical energy, "stop" and "go" signaling lamps, conductors for operatively connecting said lamps with said source, circuit controller mechanism associated with said conductors for operation from said source and for alternately closing respective current paths for said lamps continuously throughout desired intervals measured by the running of said mechanism, in combination with means operable responsive to running of said mechanism 25 during continuous closure of the connection for said "go" lamp for repeatedly effecting a series of comparatively brief closures of the connection to said "stop" lamp, the durations of said closures and of the time intervals therebetween progressively decreasing, to indicate the increasing proximity of the termination of such continuously effective closure.

2. In a signaling system, a source of electrical energy, "stop" and "go" signaling lamps, conductors for operatively connecting said lamps with said source, circuit controller mechanism associated with said conductors for operation from said source and for alternately closing respective current paths for said lamps continuously throughout desired intervals measured by the running of said mechanism, in combination with means operable responsive to running of said mechanism during continuous closure of the connection for said "go" lamp for repeatedly effecting a series of comparatively brief closures of the connection to said "stop" lamp, said closures separated by time intervals of progressively decreasing duration, whereby to indicate the increasing proximity of the termination of such continuously effective closure.

3. In a signaling system, a source of electrical energy, "stop" and "go" signaling lamps, conductors for operatively connecting said lamps with said source, circuit controller mechanism associated with said conductors for operation from said source and for alternately closing respective current paths for said lamps continuously throughout desired intervals measured by the running of said mechanism in combination with means operable responsive to running of said mechanism during and adjacent a terminus of the continuous closure of the connection for one of said lamps for repeatedly effecting a series of comparatively brief closures of the connection to the other of 50 said lamps, which connections are effective for time intervals, measured by the running of said mechanism and of progressively decreasing duration.

4. In a signaling system, means for displaying a 75

- plurality of signaling aspects, each aspect effective between some predetermined termini for indicating occasion for permissive and restrictive governing of an activity, circuit controller mechanism associated with said means for rendering said aspects alternately effective throughout intervals measured by the running of said mechanism, in combination with means operable at a progressively increasing speed for causing intermittent display of a signaling aspect at a progressively increasing frequency and for progressively decreasing durations during and adjacent an interval terminus whereby to indicate the proximity of said terminus.
5. In a signaling system, signals for displaying diverse aspects, each aspect effective between some predetermined termini for indicating occasion for permissive and restrictive governing of an activity, mechanism operable for establishing times 10 for varying the display of said signaling aspects, in combination with means for effecting, during a portion of the display of one of said signaling aspects, a series of comparatively brief displays of another of said signaling aspects and 15 whereby said brief signal displays will be separated by time intervals of progressively decreasing

duration, whereby to indicate the increasing proximity of the impending change.

6. In a traffic signaling system comprising signals having diverse aspects for governing traffic movements, means operable for effecting displays 5 of said signals in accordance with a predetermined sequence of presentation, in combination with means for effecting intermittent display of one of said signals, for indicating the proximity of a change of signal display pursuant to said sequence of presentation, such intermittent displays characterized by progressive decreases of durations and of time intervals therebetween.

7. In a traffic signaling system comprising signals having diverse aspects for governing traffic 15 movements, means operable for effecting displays of said signals in accordance with a predetermined sequence of presentation, in combination with means for effecting intermittent display of one of said signals for indicating the proximity of 20 a change of signal display pursuant to said sequence of presentation, such intermittent displays characterized by progressive decreases of the durations thereof.

25

ERNEST R. FREEBERG.
